ATTORNEY

UNITED STATES PATENT OFFICE.

IVAN F. SELSTROM, OF STOCKETT, MONTANA.

HAND-LEVER.

1,257,749.

Specification of Letters Patent. Patented Feb. 26, 1918.

Application filed March 28, 1917. Serial No. 158,003.

To all whom it may concern:

Be it known that I, IVAN F. SELSTROM, a citizen of the United States, residing at Stockett, in the county of Cascade and State 5 of Montana, have invented certain new and useful Improvements in Hand-Levers, of which the following is a specification.

This invention relates to manually operated levers and more particularly to locking 10 means which may be associated with the lever of any ordinary wagon brake.

An object of this invention is to provide means engageable with the brake lever of a wagon or other vehicles, to prevent accidental 15 movement of the same, as is frequently occasioned by the jolting of the wagon body when the vehicle is in motion.

Another object is to provide a device of the character mentioned which can be readily 20 applied to brake levers now in use, without necessitating any modification of the latter.

A further object is to provide a device of the character described, the several parts of 25 which are of such simple construction, that the cost of manufacture will be reasonably low.

The above and additional objects, as well 30 as the construction, arrangement and operation of the parts, of the preferred form of my invention, will be more clearly understood from the following specification and accompanying drawings. In the drawings:

Figure 1 is a top plan view of a portion 35 of a conventional form of wagon and illustrates the application of the device constructed in accordance with my invention.

Fig. 2 is a side view.

Fig. 3 is an end view and

Fig. 4 is a sectional view taken longitudinally through the spring housing.

In the drawings the numeral 1 indicates a quadrant having its laterally extending side portions 2 and 3 equipped with downwardly 45 extending base portions 4 and 5 by means of which the quadrant is secured to the wagon body as shown in Fig. 1. The quadrant is further provided on one of its lateral margins with a toothed rack 6, adapted to 50 be engaged by the brake lever 7 which is secured to the wagon in the usual manner.

For the purpose of preventing the brake lever 7 from becoming accidentally disengaged from the rack 6, when once engaged 55 therewith, I have provided an elongated rod 8 of a length somewhat greater than the dis-

tance between the side portions 2 and 3 of the quadrant. The bar 8 engages and exerts a yielding pressure against the lever 7 and has its opposite ends received in suitable 60 housings 9 and 10, mounted on the opposing sides of the quadrant as clearly shown in Fig. 1. The housings 9 and 10 may be cast, stamped from sheet metal or otherwise formed, and each comprises a top, side and 65 end walls, the latter being provided with outwardly extending foot members adapted to be fastened to the sides of the quadrant. In the preferred form shown, each of the housings are formed from a single piece of 70 metal bent to form the top 11, sides 12 and end walls 13 the latter being equipped at their lower marginal edges with outwardly turned foot portions 14. One side of each housing is cut or otherwise provided with a 75 slot 15.

In the assembled view shown in Fig. 1 the housings are secured to the lateral sides of the quadrant by means of suitable fastening means engaging the foot portions 14 80 and are so disposed that the slotted sides of the housings face one another. The ends of the rod 8 extend through the slots in the housings and are engaged by suitable springs 16 mounted in the housings, which normally 85 force the rod into engagement with the brake lever, the springs 16 each having one terminal thereof resting against the end of the housing opposite the slotted end and the other terminal engaging the end of the rod 90 8 and normally forcing the same to the limit of the slots 15 the latter being sufficiently elongated to permit the necessary movement of said rod.

The rod 8 when forced to the limit of the 95 slots 15 by the springs within the housings 9 and 10, exerts sufficient pressure against the lever 7 to keep the same firmly in engagement with the rack 6 and prevent any accidental movement of the said lever. To 100 operate the lever in the usual manner it is only necessary to pull the same in the direction of the rod 8 with sufficient force to overcome the resistance of the springs, and the lever may then be moved to the required position. Fig. 4 shows the preferred manner of adapting the ends of the rod 8 for engagement with the springs. The end of the rod, positioned within the housing is shaped 105 to provide a bearing against which an end 110 of the spring abuts, as indicated at 17.

I do not limit myself to the specific con-

struction shown but reserve the right to resort to such changes in the form and arrangement of the parts as may come within the scope of the appended claims.

5 I claim:

1. The combination with a toothed rack having side portions adapted to be secured to a support, a lever movable into and out of engagement with said teeth, a housing

10 secured upon each of said side portions, springs arranged within said housing, a rod bearing against said lever and having its opposite ends received in said housing and adapted to be engaged by said springs, said 15 rod normally holding said lever in engagement with the rack.

2. A device of the character described, including a rack bar, a lever movable into and out of engagement with said rack bar, casings mounted on said rack bar, springs positioned within said casings, and a rod having its opposite ends movably mounted in said casings and engaged by said springs, said rod contacting with said lever.

25 3. A locking device including a toothed rack bar having its ends bent at right angle

and extended in parallelism, a casing mounted upon each of said angular ends, said casings being provided with opposing slots, a pressure bar supported in parallelism with the toothed portion of said first mentioned bar and having its opposite ends slidably mounted in said slot, and springs positioned in each of said casings and engaging the ends of said bar.

30 4. A locking device, including a toothed rack bar having angularly extended end portions, a casing mounted upon each of said end portions and having a slot formed therein, a pressure bar supported between said casings and having its ends received in said slots, enlargements formed on the ends of said bars, and springs positioned in each of said casings and engaging said enlargements.

35 In testimony whereof I affix my signature in presence of two witnesses.

40 IVAN F. SELSTROM.

45 Witnesses:

FROST P. SELSTROM,
ARO ANTHONY.
